UNITED STATES PATENT OFFICE.

JEAN PAUL DUCASSOU, OF PARIS, FRANCE.

SCREW-PROPELLER.

SPECIFICATION forming part of Letters Patent No. 675,722, dated June 4, 1901.

Application filed May 19, 1900. Serial No. 17,273. (No model.)

To all whom it may concern:

Be it known that I, JEAN PAUL DUCASSOU, engineer, a citizen of the Republic of France, and a resident of 195 Boulevard Pereire, Paris, 5 in the Republic of France, have invented a new and useful Improvement in and Relating to Screw-Propellers for Ships, Boats, and the Like, which is fully set forth in the following specification.

10 This invention has reference to screw-propellers for ships or boats, and has for its object to render the propeller readily adjustable as to position in accordance with the direction it is desired to impart to the vessel.

15 In order that my invention may be clearly understood and readily carried into effect, I will describe the same fully with reference to the accompanying drawings, in which—

20 Figures 1 and 1^a represent a vertical section of my improved propeller arrangement secured to the stern of a boat of any description, and Fig. 2 is a horizontal section on line X Y of Fig. 1^a.

25 To render my improved propeller applicable for all cases and to be manipulated by unskilled persons, I have arranged it so that it can be fixed to any boat in a comparatively short time.

30 In order to avoid complication in the mechanism for reversing the direction of travel of the vessel, which in existing arrangements can only be effected by first stopping the motor or by a special and cumbersome mechanism which is necessarily heavy and complicated,

35 I have devised the following propeller arrangement, which is of great simplicity and permits of turning around in one place, of going ahead or astern, and generally in any direction without being obliged to stop or to alter the speed of the motor or of the propeller, and this by the simple rotation of the box carrying the propeller.

40 The apparatus comprises the boxes *a* and *b*, connected together by a tube *c*, the box *b*, carrying the propeller, being capable of performing a rotary motion around the tube *c* when operated by a gear-wheel *d*, firmly secured to the box and gearing with a pinion *e*, operated from the boat in any suitable manner. The 45 shaft *g* of the motor *o* carries bevel-pinion *h*, gearing with a pinion *i*, keyed to the shaft *j*, which latter carries a pinion *k*, adapted to

55 gear with a pinion *l*, thus rotating the shaft *m* and propeller *n*. It will be obvious that the transmission of the movement from the motor to the propeller is not in any way impeded by the rotary motion of the box *b*.

60 Upon the tube *c* is fixed a bracket *p*, secured by screws to the keel or stern post of the boat for the purpose of holding the arrangement in position, while in combination therewith the motor *o* is fixed upon the rear seat at the stern of the boat.

65 The operation of my improved device is as follows: Upon the rotation of the shafting *f* the propeller is caused to occupy any one of the principal positions 1 2 3 4 (shown in Fig. 2) or any intermediate position, as may be desired. The position 1 causes the boat to travel ahead, position 2 causes the boat to 70 turn to the right, position 3 causes the boat to travel astern, and position 4 causes it to turn to the left.

75 If it is desired to stop the vessel while allowing the propeller to rotate, it suffices to revolve the box *b* in a continuous manner either in one direction or the other.

80 The shaft *f* may be driven by flexible shafting *q* or by ordinary shafting through the intervention of a fly-wheel rotated in any appropriate manner from the boat, and which for the purpose of effecting the rotation of the box *b* may be driven by means of a hand-wheel *s* and strap *t*, the said hand-wheel being also capable of being used for starting 85 when using a petroleum-motor.

What I claim is—

1. In a propeller for vessels, the combination with two boxes fixed to the stern of the vessel, the lower end being provided with a gear-wheel, and a tube connecting said boxes, of suitable shafting journaled in said boxes and tube, a screw-propeller operated by the shafting, a pinion meshing with said gear-wheel, and a suitably-operated flexible shaft 90 for turning said pinion, whereby the box carrying the propeller-shaft is rotated, substantially as set forth.

2. In a propeller for vessels, the combination with two boxes fixed to the stern of the vessel, the lower box being provided at the top with a gear-wheel, and a tube connecting the said boxes, of suitable shafting journaled in said boxes, a screw-propeller operated by

the shafting, a pinion meshing with said gear-wheel, a suitably-operated bent flexible shaft for turning said pinion, and means for connecting the said shafting and the flexible shaft, whereby the box carrying the propeller-shaft is rotated, substantially as set forth.

5 In testimony whereof I have signed this

specification in the presence of two subscribing witnesses.

JEAN PAUL DUCASSOU.
